[57] CLAIM

The ornamental design for a cosmetic container for
non-liquid cosmetics, substantially as shown and de-
scribed.

DESCRIPTION

FIG. 1 is a top plan view of a cosmetic container for
non-liquid cosmetics in closed position showing our
new design.

FIG. 2 is a top plan view thereof in open position.

FIG. 3 is side view thereof in closed position.

FIG. 4 is side elevational view thereof in open position.
FIG. 5 is a front elevational view thereof in closed position.

FIG. 6 is a bottom plan view thereof.

FIG. 7 is a rear elevational view thereof in closed position.
